UNITED STATES PATENT OFFICE.

GEORGE SEYMOUR MAXWELL, OF NEWARK, NEW JERSEY, ASSIGNOR, BY DIRECT AND MESNE ASSIGNMENTS, TO THE TAXIMETER REGISTER COMPANY, OF WASHINGTON, DISTRICT OF COLUMBIA, A CORPORATION OF DELAWARE.

RECORDING-TAXIMETER.

1,138,680.

Specification of Letters Patent.

Patented May 11, 1915.

Application filed October 16, 1911. Serial No. 654,830.

To all whom it may concern:

Be it known that I, GEORGE S. MAXWELL, a citizen of the United States, residing at Newark, in the county of Essex and State of New Jersey, have invented certain new and useful Improvements in Recording Taximeters, of which the following is a specification.

My invention relates to improvements in recording taximeters.

The object of my invention is to devise a simple form of recording mechanism in combination with a taximeter whereby a record may be kept of all the facts necessary for a vehicle owner to know in order to control the manner of operating the vehicle from day to day, and at the same time this result is attained with a small amount of additional mechanism, so as to produce a device which will be durable, and relatively economical in construction and operation.

With these general objects in view my invention, broadly considered, consists of the combination with the elements necessary to constitute a taximeter, of means for holding and moving a record sheet of any kind, such, for example, as a web or tape, and a pair of recording devices arranged to mark the record sheet, one recording a series of wave-like lines continuously during the movement of the vehicle, and being actuated from a wheel of the vehicle, while the other merely marks a line on the sheet, the position of the line being determined by the position of said recording device with relation to the sheet, such position being controlled by the setting arm of the taximeter, which serves to throw the indicating mechanism of the taximeter into and out of operation. The record sheet is most advantageously fed by a clock-mechanism of the usual type.

A further feature of my invention consists in means for rewinding the clock from the device which drives the taximeter register, so that whenever the clock spring has run down it will be automatically wound up during the travel of the vehicle.

In the drawings,—Figure 1 is an elevation partly in section of so much of a taximeter as is necessary to illustrate my invention; Fig 2, a side elevation of the mecha-

nism shown in Fig. 1; Fig 3, a plan view of the record sheet holding mechanism with 55 the markers; Fig. 4, a view of a piece of a record sheet with a record formed thereon; and Figs. 5, 6 and 7, detail views of the clock-winding mechanism.

Referring to the drawings, A is a casing 60 divided by a partition *a* into an upper and a lower compartment. The lower compartment contains any usual form of taximeter and registering mechanism arranged to be driven from the vehicle wheel and to be set 65 for different conditions of service by a suitable manually-operated setting mechanism. As such mechanisms are well known and in general use, I have only indicated the mechanism in a general way in the drawings. For example, the fare registers are shown in outline as ordinary disk registers, at B, Fig. 1, and the register mechanism has a worm wheel B' in mesh with a worm B² fixed on a vertical driving shaft B³ arranged 70 to be driven in the usual way by a flexible shaft from the vehicle wheel. The coupling for the flexible shaft is indicated at B⁴ and is of any ordinary type.

The manually operated setting mechanism 80 comprises the usual flag or setting arm C, fixed to a setting shaft C' and arranged to set the register mechanism so that it will register at different rates, depending upon the extent to which the setting arm C is 85 moved angularly. It is common to have the setting mechanism and the register mechanism so arranged that the register can be set to operate under four different conditions, namely, first, not operating or idle, 90 even though the vehicle be moving, second, operating at a given rate to register the charge for one or two passengers, third, operating at a second rate to register the charge for three or four passengers, and, 95 fourth, with the register disconnected from the vehicle wheels and connected to a clock mechanism whereby the register operates to register the charge according to a time rate. In the drawings the clock mechanism is indicated generally at D, its winding arbor, indicated at D', being shown as provided with a bevel gear wheel d, in mesh with a bevel gear wheel d' mounted on the spindle of a rewinding apparatus, whereby the clock 100 spring is wound up by the movement of the

vehicle as soon as the clock spring has run down. As this rewinding mechanism forms a part of my present invention it will be described in detail hereinafter. The taximeter 5 register mechanism also comprises an indicator, E, operated by the setting arm C to show the rate of charge being made by the register mechanism, as is usual, and in addition comprises a register of extra charges, 10 indicated at F and which may be manually operated by a rod f having a knob f' at the back of the casing. (See Fig. 2.)

As hereinbefore stated the particular details of construction of the taximeter 15 register mechanism form no part of my present invention and only so much thereof has been illustrated and referred to as is necessary for a full understanding of my invention, which will now be described.

20 On the driving shaft B³ is fixed a cam G having an inclined lateral surface g, against which bears a roller g' mounted on a stud g² projecting laterally from a rod G' which is slidably mounted in a guide a' carried by 25 the partition a, the said rod G' extending through said partition as shown in Fig. 1. The rod G' is pressed downward yieldingly by a spring g³ bearing against a collar g⁴ on the rod and against the guide a', whereby 30 the roller g' is kept in contact with the operating surface g of the cam G, so that as the driving shaft B³ and the cam G rotate, the rod G' is reciprocated in its guide a'. To the upper end of the rod G' is attached a 35 swinging arm H which is yieldingly pressed toward a traveling record sheet I by any suitable means, for example, by a coiled spring h connected to the arm H and to the rod G'. The arm H is provided with a 40 socket h', Fig. 2 for holding a suitable marking instrument h² such as a point of some suitable metal which will make a mark on paper, for example lead. It is evident that by means of the arrangement above de- 45 scribed, rotation of shaft B³ produces rectilinear reciprocating movement of the rod G', and hence of the marking instrument h², the motion of the marker taking place parallel to the surface of the traveling record 50 sheet and transversely to the movement thereof. The partition a also carries another rod guide a², in this case extending upward from the partition. Through this guide extends a rod, K which is capable of 55 moving longitudinally in its guide a² and of rotating therein for a purpose hereinafter described. The lower end of this rod is provided with a head k which rests upon a lever K' fulcrumed at k' and having its free end 60 bearing on a stepped cam K², fixed on the setting shaft C'. The rod K is surrounded by a helical spring k² secured at its lower end to the rod and at its upper end to the partition a, this spring k² serving not only

to force the rod K yieldingly against the 65 lever K' but also tending to rotate said rod about its axis. To the upper end of this rod is secured a marking arm L, provided with a socket l carrying a suitable pencil or marker l' which is held yieldingly against 70 the record sheet I by the tendency of the spring k² to rotate the rod K. The stepped cam K² has four operating surfaces of different radii, as will be clear from Fig. 2, so that when the setting shaft C' is rotated 75 by means of the setting arm C the lever K' and rod K, together with the marking arm L, will be raised or lowered to different positions, whereby the relative position of the marker or pencil l' on the record sheet will 80 be determined by the rate of charge for which the taximeter register is set.

The record sheet is moved relative to the pencils or markers in any suitable way. For example, in the present device which shows 85 the record sheet as a tape or web of paper, the mechanism for holding and moving the record sheet is as follows: To the hour arbor, d² of the clock mechanism D is fixed a bevel wheel d³ meshing with a companion bevel wheel d⁴ on a reel-driving shaft M which extends upward through the partition a and is provided at its upper end with a driving wheel m having a slightly roughened or toothed periphery. A lever N, Fig. 3, ful- 90 crumed at n carries a reel or spool arbor on which is loosely mounted a spool n² on which the record web may be wound. To a pin on the lever N is connected one end of a spring n³ having its other end extended through the 95 center of a thumb-screw n⁴ threaded through a post n⁵, fixed in the partition a. By means of the thumb-screw n⁴, the tension of the spring may be adjusted, so that the reel of paper web may be pressed in contact with the 100 roughened edge of the reel driving wheel m. To the upper surface of the partition a 105 is secured a cylindrical roll holder P, open at the top and having a slit p at one side, into which a spool of paper web may be in- 110 serted in an obvious manner, its free end carried out through the slit p, and inserted in a slit, n⁶, in the spool n², whereupon said spool is rotated to wind up the web to a sufficient extent to hold it from slipping. 115 Between the spool n² and the roll-holder P the paper web I passes over a standard P' against which the paper is pressed by the marking pencils or points. The web of paper may be ruled with longitudinal lines 120 dividing it into a series of spaces as indicated in Fig. 4 of the drawings, and may have printed on the top edge a series of numbers indicating the respective hours and smaller intervals, to aid in reading the 125 record.

In Fig. 4 the record sheet or web is shown as provided, at the left hand edge, with leg-

ends indicating the purpose of the various longitudinal spaces, but this is not absolutely necessary and is generally omitted.

From the description of the record mechanism it will be seen that the web or record sheet I is moved continuously by the clock, and that the markers or pencils, h^2 , l' , are arranged to make continuous registering contact with the sheet and thus will mark said sheet at all times when the clock is running. When the vehicle is moving, the cam G will reciprocate the lower pencil h^2 , and cause it to mark a wave-like or saw-tooth line on the record sheet, the slope of the line varying according to the speed of the vehicle. In the portion of the record sheet shown in Fig. 4, the extreme range of the marker transversely of the strip is supposed to correspond to one-half mile travel of the vehicle although, of course, this will depend upon the number of revolutions of the cam G relative to a unit of distance traveled by the vehicle. When the vehicle is not moving, the lower pencil merely marks a straight line on the paper, and the length of such line indicates the duration of time when the vehicle was standing. The upper pencil l' records the condition of the taximeter register, and thereby of the conditions of service under which the vehicle was employed at different times and also the length of service under each condition.

The manner of reading the record sheet is made clear by Fig. 4. For example, an examination of the record sheet illustrated in that figure shows that at 8 o'clock the vehicle was standing, as appears from the straight line at the lower part of the sheet, and that it was not then employed, as shown by the straight line in the longitudinal division marked "Idle". At about two minutes past eight o'clock the vehicle commenced to travel about as shown by the saw-toothed or wave lines at the lower part of the sheet, but still was not engaged by a passenger, as shown by the straight line in the space marked "Idle". The said wave lines indicate that the vehicle traveled about $1\frac{1}{2}$ miles while unemployed between about 8:02 and 8:08, showing an average speed of about $18\frac{1}{2}$ miles per hour during this time. At the termination of this period the vehicle was hired for carrying one or two passengers, as shown by the straight line in the space marked "First" and was so employed until about 8:13, traveling about $\frac{1}{2}$ mile under this employment when it was discharged and stood idle for a few minutes, then traveled for a few minutes, again stood still for a short interval, again traveled for a few minutes, until about 8:25 it was engaged by three or four passengers, as shown by the straight line in the space marked "2nd" and traveled about $1\frac{1}{2}$ miles before being dis-

charged by said passengers, about 8:30. 65 Thereafter it stood idle until about 8:40 when it was hired on a time service as shown by the straight line in the space marked "Time" and during this interval, so far as can be determined from the piece of record shown, it was standing at three different intervals, and was traveling during the intermediate intervals, as shown by the lower record. 70

From the above explanation it will be seen 75 that the record made by the lower marker, shows the movement or non-movement of the vehicle, while the record made by the upper marker, shows the condition of the service in which the vehicle was engaged, 80 the time characters on the sheet determining the time of each condition. The combined record produced by the markers on the recording web or tape thus expresses continuously the relation between the speed of the vehicle and the tariff conditions under which the vehicle is being operated. From this it is obvious that the record gives the details of service in a very clear and complete manner, so that with such a recording apparatus 90 an owner may control the operation of his vehicle by the driver and may readily determine the amount of fares which he should be entitled to receive.

My improved clock-rewinding device is 95 constructed as follows: The bevel pinion d' which meshes with the bevel pinion d on the spring arbor of the clock, is fixed to a spindle R, (shown in elevation in Fig. 6) which is tubular at its lower portion, as 100 shown in Fig. 5, and has its extreme lower end reduced in diameter, as indicated at r . Just above this reduced portion the spindle is provided with transverse slots r' , Fig. 5. Within the tubular portion there is mounted 105 a plunger, r^2 , held in place in the tube by a cross-pin r^3 which is guided in the slots r' , whereby the plunger r^2 may move to a limited extent longitudinally but cannot rotate in the tube, the said pin r^3 having its ends extending outside the spindle. The extreme lower end of the reduced portion r is provided with notches one of which is indicated at r^4 , Fig. 6, these notches being ratchet-shaped. The spindle R has its upper portion screw-threaded as shown at r^5 , and upon this is screwed a sleeve, S, having an annular flange s at the lower end, and diametrically opposite slots s' extending longitudinal of the sleeve, from the top end downward for a portion of the length of the sleeve. See Fig. 7. The upper portion of the sleeve is mounted in a bearing or guide T, Fig. 5, fixed to any suitable part of the frame work or casing, each guide having 115 pins or keys t , which project into the respective slots s' of the sleeve and thus prevent rotation of the sleeve while at the same time

permitting longitudinal movement thereof. The lower flanged end of the sleeve is received in the hollow socket portion of a movable coupling member U, having a cap u 5 screwed in place and provided with a hole through which the sleeve passes snugly but loosely. The said movable coupling member U is splined to the spindle R, as indicated at u' whereby the rotation of the coupling 10 will rotate the spindle, and vice versa, the splined connection allowing a longitudinal movement of the coupling member U on the spindle. Between the cap u and the flange s of the sleeve there is mounted a helical 15 spring U' which tends to hold the movable coupling member U upward, while a spring U² mounted in the socket below the flange s tends to force the movable coupling member U downward. The cap u has an exterior 20 diameter somewhat greater than that of the coupling member U, whereby a shoulder is formed as indicated at u². A spring catch u³ fixed at one end to a suitable part of the framework of the apparatus and adjustable 25 by means of a screw, u⁴, is provided with a hook u⁵ arranged to engage the shoulder u² formed by the cap whereby the movable coupling member U may be held up against the action of the spring U², but when the tension of the said spring becomes too great, 30 the spring catch is forced to one side thus freeing the shoulder u² and allowing the spring U² to push the movable coupling member U downward. To the lower reduced end r of the spindle is attached a driving wheel such as the worm wheel V, which is continuously driven by the movement of the vehicle, as for example by the worm V' on the cross-shaft V² actuated from 35 the driving shaft B³ through the worm wheel V³ and worm V⁴. The upper side of the driving wheel V and the lower end face of the movable coupling member U are provided with coacting clutch devices, for example, the pins r, r', which are slightly tapered or coned as shown. A key W is provided for winding the clock by hand if desired at any time when the vehicle is stationary. This key W, Fig. 5, has a cylindrical end arranged to enter the tubular lower end of the spindle R, whereby the plunger, r², is pushed upward, thus causing the cross-pin r³, to push the movable coupling member U upward against the tension of the 45 spring U', whereby the clutch devices or pins, r, r', are separated. The key W also has a cross-pin or shoulder w which engages the ratchet notches r⁴, in the lower end of the spindle R so that when the key W is inserted and rotated in the proper direction, first the coupling U is lifted to release its clutch members from those of the driving wheel V and then the spindle R is rotated to wind the clock. The screw-thread connection between the spindle R and the sleeve S is such that as the spindle is rotated to wind the clock spring, the sleeve is moved upward, thus tending to compress the spring U' above the flange s which spring in turn forces the movable coupling member upward until its shoulder, u², is caught and held by the hook of the spring catch, u³, thus holding the clutch members apart. In this condition the clock is freed from the driving wheel V and may operate in the usual way. 70 As the clock runs down, the spring arbor is rotated in the opposite direction to that which it had when being wound up. Consequently, it rotates the spindle R in such a direction as to cause the screw thread to move the sleeve S downward, this movement going on relatively slowly. The downward movement of the sleeve S compresses the spring U² below the flange s, the compression of the spring gradually increasing and tending to drive the movable coupling member U downward, which tendency is at first resisted by the spring catch, u³, until finally the pressure of the spring U², becomes great enough to overcome the spring catch, u³, which releases the shoulder u² and thereupon the spring U² drives the member U downward and the clutch devices or pins, r', of the movable coupling device engage the clutch devices or pins, r, of the driving wheel V. If the vehicle is in motion, the driving wheel V will rotate the clutch member U and thus rotate the spindle R which will wind up the clock spring. Also the rotation of the spindle R will, by the action of its screw thread, move the sleeve S upward. This tends to compress the spring U' above the flange s. Such compression occurs merely because of the frictional engagement between the clutch devices or pins. When the 105 said spring U' has been compressed to such an extent as to overcome this frictional engagement it moves the movable clutch-member upward suddenly with sufficient force to cause the shoulder u², to engage the hook of the spring catch u³ which then holds the movable clutch member out of engagement with the driving wheel V. It will be seen that by means of this self-winding device the clock is automatically wound up by the movement of the vehicle. The extent to which the clock spring is wound depends upon the extent of rotation of the spindle and this is determined by the tension of the springs U' and U². 110

Having thus fully described my invention, what I claim is:

1. In a taximeter, the combination, with the taximeter clock mechanism, the register-setting device and the register-driving shaft, arranged to be operated by the movement of the vehicle, of means for holding and moving a record sheet, connections between the

- clock mechanism and said means whereby the latter is operated, a reciprocatory marker arranged to mark on one part of the record sheet, means operated by the register driving shaft for reciprocating said marker in continuous contact with said record sheet, a second marker arranged to mark continuously on another part of the record sheet, and means operated by the movement of the 5 register-setting mechanism for adjusting said second marker in a direction transverse to that of the movement of the record sheet, the record produced on the sheet by said markers expressing at all times the relation between the speed of the vehicle and the tariff 10 conditions under which the vehicle is operated.
2. In a taximeter, the combination, with the taximeter clock mechanism, the register-setting device and the register-driving shaft arranged to be operated by the movement of the vehicle, of means for holding and moving a record sheet, connections between the clock mechanism and said means whereby 15 the latter is operated, a reciprocatory marker arranged to mark on one part of the record sheet, means operated by the register-driving shaft for reciprocating said marker in continuous contact with said record sheet, a second marker arranged to mark continuously on another part of the record sheet, a stepped cam arranged to be adjusted by the movement of the register-setting device, and connections between said stepped cam and 20 the said second marker, whereby the latter is adjusted transversely of the direction of movement of the record sheet, according to the position of the register-setting device, the record produced on the sheet by said 25 markers expressing at all times the relation between the speed of the vehicle and the tariff conditions under which the vehicle is operated.
3. In a taximeter, the combination, with the taximeter clock mechanism, the register-setting device and the register-driving shaft arranged to be operated by the movement of the vehicle, of means for holding and moving a record sheet, connections between 30 the clock-mechanism and said means whereby the latter is operated, a reciprocatory marker arranged to mark on one part of the sheet, a cam device rotated by the register-driving shaft, means operated by the cam-device for reciprocating said reciprocatory marker in a straight line and in continuous contact with said record sheet, a second marker arranged to mark continuously on the record sheet at another part, and means 35 actuated by the register-setting device for adjusting said second marker transversely to the direction of movement of the record sheet, the record produced on the sheet by said markers expressing at all times the relation 40 between the speed of the vehicle and the tariff conditions under which the vehicle is operated.
4. In a taximeter, the combination, with the register-setting means and the register-driving means arranged to be operated by the movement of the vehicle, of means for holding and uniformly moving a record sheet, a pair of markers arranged in a line transverse to the movement of the sheet, means operated by the register-driving means for reciprocating one marker transversely to the movement of the record sheet, and means actuated by the movement of the register-setting means for adjusting the other marker transversely of the movement of the record sheet and to different extents, both markers being arranged to make continuous registering contact with said sheet and to produce a record thereon expressing at all times the relation between the speed of the vehicle and the tariff conditions under which the vehicle is operated. 45
5. In a taximeter, the combination, with the register-setting means and the register-driving means arranged to be operated by the movement of the vehicle, of means for holding and uniformly moving a record sheet, means operated by the register-driving means for giving one marker rectilinear reciprocative movement transversely to the movement of the record sheet, and means actuated by the movement of the register-setting means for adjusting the other marker transversely of the movement of the record sheet and to different extents, both markers being arranged to make continuous registering contact with said sheet and to produce a record thereon expressing at all times the relation between the speed of the vehicle and the tariff conditions under which the vehicle is operated. 50
6. A taximeter comprising the combination, with clock mechanism, a recording tape or web arranged to be moved longitudinally thereby, an adjustable tariff-registering device comprising a marker adapted to make continuous tariff-registering contact with said tape, and means for moving said marker transversely of said tape to set the marker in different tariff-registering positions, of a second marker adapted to make continuous speed-registering contact with said tape and capable of movement transversely of the tape, and means operable by travel of the vehicle on which the taximeter is mounted for reciprocating said second marker transversely of the tape at a rate proportional to the speed of the vehicle, the arrangement being such that the combined record produced by said markers on the tape expresses continuously the relation between the speed of the vehicle and the tariff conditions under which the vehicle is operated. 55
7. In a taximeter, the combination, with the tariff conditions under which the vehicle is operated. 60

the clock mechanism having a clock-spring and arbor, and the register-driving means arranged to be actuated by the movement of the vehicle, of a winding means including a 5 spindle connected to the clock-spring arbor, said spindle being screw-threaded, a clutch member driven by the register-driving means, and a movable clutch member having a screw-thread engaging the thread of

the spindle and arranged to engage with 10 and be disengaged from the other clutch member.

In witness whereof I have hereunto affixed my hand.

GEORGE SEYMOUR MAXWELL.
